UNITED STATES PATENT OFFICE.

FRED R. TAISEY, OF INDIANAPOLIS, INDIANA, ASSIGNOR TO THE LAMSON CONSOLIDATED STORE SERVICE COMPANY, OF BOSTON, MASSACHUSETTS, A CORPORATION OF NEW JERSEY.

PNEUMATIC-DESPATCH APPARATUS.

No. 852,913.

Specification of Letters Patent.

Patented May 7, 1907.

Application filed May 24, 1906. Serial No. 318,474.

To all whom it may concern:

Be it known that I, FRED R. TAISEY, of Indianapolis, county of Marion, and State of Indiana, have invented a certain new and useful Pneumatic-Despatch Apparatus; and I do hereby declare that the following is a full, clear, and exact description thereof, reference being had to the accompanying drawings, in which like letters refer to like parts.

10 The object of this invention is to provide an improved terminal for pneumatic despatch apparatus, where a carrier director projects into the passage-way through the terminal and deflects a carrier through the 15 discharge opening of the terminal when said carrier is so formed as to lock the director in position, the locking arrangement being such as to be actuated by a differently formed carrier so that the latter will move the director 20 out of the way and pass.

The various features of this invention will be more fully understood from the accompanying drawings and the following description and claims.

25 In the drawings, Figure 1 is a central longitudinal section through a terminal in the despatch apparatus the parts being in normal position. Fig. 2 is a central longitudinal section through a terminal with the director fully operated by one carrier and the other carrier being stopped. Fig. 3 is the same but showing the director locked and the carrier being discharged from the terminal. Fig. 4 is an elevation of a portion of a 35 pneumatic despatch apparatus, parts being in section. Fig. 5 is a transverse section on the line 5—5 of Fig. 1, excepting that no carrier is shown in Fig. 5. Fig. 6 is an elevation of the rear part of a director and associated parts for stopping the carrier while the director is elevated. Fig. 7 is a detail on a large scale of a portion of the director and a locking-trip thereon.

40 The part of a pneumatic despatch apparatus which is shown consists of a straight portion 10, semicircular portions 11, a terminal 12, out-going portions 13 and 14 and a second terminal 15.

45 The terminal 12 has an extension 16 at one side with a discharge opening 17 therethrough that is closed by a valve or clapper 18 closed by a spring 19 and by suction. A guide 20 is pivoted in the discharge opening

so that the inner edge thereof will be flush with the interior surface of the passage-way 55 through the terminal.

Opposite the discharge opening there is a narrow chamber 25 in a casing 26, and in this chamber I pivot a director 27 by a pin 28 which has a spring 29 on it that causes one 60 end of the director to project at an inclination across the passage-way for the carriers 30 and 31. To the casing 26 there is secured a fixed stop 32 in position to be engaged by a locking-trip 33 that is pivoted between its 65 ends on a pin 34 to the director and is returned to normal position against a stop 35 by a spring 36 whenever said locking-trip is actuated.

As seen in Fig. 2 the carrier 30 has on its 70 head a central projection 37 that is adapted to engage the lower end of the locking-trip 33 before the head of the carrier engages said director. When the locking-trip is actuated, first it assumes the position shown in Fig. 2 75 and engages the fixed stop 32, and then the carrier is deflected by the director through the discharge opening. The carrier 31 has no projection 37, consequently its head comes in contact with the director 27 before 80 the locking-trip is engaged. The director is then thrown up out of the way, from the dotted line position shown in Fig. 3 to the full line position, and the carrier 31 passes on. A buffer 38 receives the blow of the director 85 when it is actuated by the carrier.

To prevent one carrier following another while the director is in the locked position, I provide a carrier stop 40 pivoted on a pin 41 and actuated by spring 42 so that the outer 90 end of the stop will bear against one end of the director and the other end of the stop will project into the passage-way for carriers. A latch 44 is pivoted to the casing on a pin 45 with the free end thereof adapted to engage 95 notches in the outer end of the carrier stop 40 and the whole is set in a position to stop a carrier when the director is in the partially operated position shown in Fig. 3. An arm 46 on the end of the director engages a pin 47 100 on the latch and holds it normally in the position shown in Fig. 1, the latch being above the carrier stop and then the stop will permit the carrier to pass it. But when the director is partially operated as in Fig. 3, the spring 105 42 forces the outer end of the stop against the

end of the director as it changes position, whereupon the latch drops into the lower notch in the trip and that causes the inner end to project far enough to stop a carrier. The inner end of the stop 40 is curved, as shown, in the direction of movement of the carrier, so that when the latch 44 is elevated, the carrier will push on by the stop 40.

What I claim as my invention and desire to secure by Letters Patent is:

1. A terminal in a pneumatic despatch apparatus having a passage-way therethrough and a discharge opening, a director projecting into the passage-way therein in a position when locked to deflect a carrier through the discharge opening, and means pivoted on the deflecting end of said director which projects into the passage-way and operable by a carrier for locking the director.
2. A terminal in pneumatic despatch apparatus having a passage-way therethrough and a discharge opening and a chamber opposite the discharge opening, a director pivoted in said chamber and projecting into said passage-way, a fixed stop, and means on the deflecting end of director in position to be engaged by a carrier and moved so as to engage said fixed stop.
3. A terminal in a pneumatic despatch ap-

paratus having a passage-way for carriers, 3^c with a discharge opening, a director projecting incliningly into said passage-way in a position when locked to deflect a carrier through the discharge opening, a locking trip mounted on the deflective portion of said director so as to be normally in an unlocking position, and the carrier with a projection from the head thereof that is adapted to engage said locking-trip and move it to a locking position before the head of the carrier engages the director.

4. A terminal in a pneumatic despatch apparatus having a passage-way therethrough for carriers and a discharge opening, a plurality of carriers the deflecting end of, a director projecting into said passage-way, a fixed stop, and means pivoted on said director in a position to be engaged by a portion of said carriers and moved so as to engage said fixed stop.

In witness whereof, I have hereunto affixed my signature in the presence of the witnesses herein named.

FRED R. TAISEY.
